UNITED STATES PATENT OFFICE.

EMMET HORTON, OF ELMIRA, NEW YORK.

BASKET-MAKING MACHINE.

SPECIFICATION forming part of Letters Patent No. 760,791, dated May 24, 1904.

Application filed November 25, 1902. Serial No. 132,740. (No model.)

To all whom it may concern:

Be it known that I, EMMET HORTON, a citizen of the United States, residing at Elmira, in the county of Chemung and State of New York, 5 have invented certain new and useful Improvements in Basket-Making Machines, of which the following is a specification.

This invention relates to machines for automatically making baskets of the kind in which 10 the sides and bottom of a basket are formed from crossed pieces of wood veneer or other similar material, which are bent into shape by forming mechanism and are held in their bent or shaped condition by bands or strips of 15 wood or other similar material secured to the upper edges of the sides. In my Patents No. 578,876, of March 16, 1897, and No. 680,149, of August 6, 1901, I have shown machines of this general type, and in the machine forming 20 the subject-matter of the present invention I have embodied some of the features of invention disclosed in my patents above mentioned, as well as parts of mechanism shown in other patents granted to me.

25 The machines shown in my patents of March 16, 1897, and August 6, 1901, are especially adapted to make what are known as "square" or "quart" berry-baskets, while the machine of my present invention is especially designed 30 to make oblong baskets of crossed pieces of veneer, commonly called "till-baskets."

While the machine of my present invention is automatic in its operation and designed to make oblong baskets, I do not wish it to be 35 understood that my invention is limited to a machine entirely automatic or to a machine adapted to make oblong baskets, as many parts of the mechanism may be advantageously used in machines operated partly by hand or 40 in machines adapted to make baskets of various shapes. In this specification I will, however, describe an automatic machine as organized to make the oblong or till baskets before referred to and will sum up in the 45 claims what I believe to be the novel features of my invention separately considered, as well as in organized mechanisms for performing operations incident to the manufacture of baskets of various kinds.

50 In the operation of the machine which I

have constructed to embody my invention in the way now best known to me the body-blanks for the basket are arranged in two piles in receptacles at one side of the machine, to which receptacles they are fed at intervals 55 by automatic mechanism operated as soon as the supply of blanks in the receptacles is exhausted, or blanks may be fed to the receptacles by hand. A blank is lifted from each pile and deposited on a die, one blank being 60 placed crosswise of the other, and when thus crossed the blanks are carried by the die into position under a form of the general shape of the interior of the basket. Two bands for each basket are fed to the form and by a partial rotation of the form are wrapped around 65 it, after which the die is raised, causing the body-blanks which it carries to be bent around the form and to inclose those portions of the bands wrapped around the form. At this 70 time the body-blanks are secured to each other by a staple driven centrally through the bottom of the blanks. The form is then further rotated in such manner as to cause the bands to be wrapped around the outside of the 75 body-blanks at their upper edges, and then these bands are secured to each other and to the body-blanks by staples made from wire, just before they are driven, the nailing mechanism being so operated as to give a relatively long stroke when attaching the bands to the long sides of the oblong basket and a relatively short stroke when attaching the bands to the ends of the basket. After the 80 blanks have been bent around the form by 85 the die and the bands have been attached the die is lowered and carried away to one side to receive a new set of body-blanks. As soon as the bands are nailed to the body-blanks the basket is complete, and the form is lowered 90 to deposit the completed basket in a chute, the basket being stripped from the form by hooks carried by the upper end of the chute. The completed baskets are stacked in the 95 chute one above the other, and when a predetermined number has been reached the pile of baskets is automatically removed from the chute and deposited upon a trough, from which they may be removed by hand or automatically.

The operations above described are merely the general operations of the mechanism. They are the results of the operation of much complicated mechanism, and there are many details of construction, all of which will be hereinafter fully described.

In the accompanying drawings I have shown a machine embodying my improvements in the way now best known to me.

10 Figure 1 shows a front elevation of the machine; Fig. 2, a rear elevation; Fig. 3, a top plan, and Fig. 4 a right-hand side elevation. In Figs. 1, 2, 3, and 4 some few of the parts are omitted in order to better illustrate other parts. The remaining figures are on an enlarged scale. Figs. 5 and 6 are detail views of the basket-forming die and the crane or die carrier, Fig. 5 showing a plan and Fig. 6 a vertical section. Figs. 7, 8, 9, 10, and 11 are detail views of a modified form of die in which certain parts yield gradually to facilitate in the bending of the body-blanks. Fig. 7 shows a plan; Fig. 8 a vertical section, with the parts in the position they occupy before the body-blanks of the basket are presented to the form, while Fig. 9 shows a vertical section taken at right angles to that shown in Fig. 8. Fig. 10 shows the position of the parts as they appear when the blanks are being bent around the form. Fig. 11 shows diagrammatically the arrangement of the hinged leaves which perform the initial bending of the body-blanks. Fig. 12 is a detail view, on an enlarged scale, showing part of the mechanism for feeding the body-blanks to the receptacles under the blank-lifting mechanism and for moving the pile of baskets from the receiving-chute after a predetermined number has been completed. Fig. 13 is a view showing particularly, in front elevation, the mechanism for operating the form for delivering the bands and for feeding the wire from which the staples are made that secure the bands to the body of the basket. Fig. 14 is a detail view showing in right side elevation the wire-feeding devices of the band-nailers. Fig. 15 is a plan view of the form. Fig. 16 shows a front elevation thereof. Figs. 17 and 18 show certain details of the form. Fig. 19 is a detail view of the band-feeding mechanism. Fig. 20 is a detail view of part of the mechanism for actuating the band-plungers. Figs. 21 and 22 are detail views of the band-feeding mechanism, Fig. 21 being in front elevation and Fig. 22 in horizontal section. Fig. 23 shows a side elevation of the mechanism for lifting the body-blanks from their receptacles and depositing them upon the die. Fig. 24 is a plan view of the same. Fig. 25 is a detail view of the needle-carrying head forming part of the mechanism shown in Figs. 23 and 24. Fig. 26 is a detail view of part of the mechanism for stripping the body-blanks for the basket from the lifting mechanism and depositing them on the die. Fig. 27 shows a

front elevation of one of the nailers for securing the bands to the body-blanks, the position of the form relatively to the nailer being also indicated. Fig. 28 is a plan view of the nailer. Fig. 29 shows a longitudinal section of the same on the line 29-29 of Fig. 28. Fig. 30 is a detail view of one of the cross-heads of the nailing mechanism to which the staple-formers and anvil-operating rods are secured. Fig. 31 is a detail view showing an end elevation of one of the staple-formers and illustrating the manner in which the wire is cut into proper lengths and formed into staples. Fig. 32 shows a cross-section on the line 32-32 of Fig. 28. Figs. 33, 34, and 35 are views of the mechanism for actuating the band-nailers and for giving to them a variable or alternately long and short stroke, Fig. 33 being partly in longitudinal section, Fig. 34 being a front view, and Fig. 35 a rear view, 85 the movements of the crank-pin being indicated by the dotted circles. Figs. 36 to 40, inclusive, illustrate the mechanism for forming and driving a staple centrally into the crossed body-blanks of the basket, which I call 90 the "bottom-nailing" mechanism. Fig. 36 is a top plan view of this mechanism. Fig. 37 shows a rear elevation of the same. Fig. 38 shows a right side elevation. Fig. 39 is a detail view showing the parts of the mechanism 95 principally concerned in forming and driving the staples. Fig. 40 is a detail view of the staple-former. Fig. 41 is a front view of the gear-wheel which operates the devices that actuate the band-nailers, the form, and the 100 band-plungers. The pinions which mesh with this wheel are also illustrated in proper relative positions. Figs. 42, 43, and 44 show cross-sections of this wheel on the lines 42, 43, and 44, respectively, of Fig. 41. Fig. 105 45 is a front view of the gear-wheel which operates devices for swinging or oscillating the die-carrier or crane and for operating the mechanism for raising and lowering the crane, the pinions operated by this wheel being shown in their proper relative positions. Figs. 46 and 47 show cross-sections of the wheel on the lines 46 and 47, respectively, of Fig. 45. Fig. 48 is a diagram illustrating the manner in which the crank-pin of the nailer-actuating 110 mechanism is shifted and rotated. Fig. 49 shows a front view of the gear-wheel for operating one of the gears forming part of the mechanism for removing the pile of completed baskets from the chute and for feeding piles 115 of body-blanks to their receptacles below the blank lifting and depositing mechanism. This figure also shows the position of the pinion actuated by said gear-wheel. Figs. 50 and 51 show cross-sections on the lines 50 and 51, 120 respectively, of Fig. 49. Fig. 52 is a front view of the main driving-gear on which is secured gearing for reciprocating the chute carrying the bottom-nailer toward and from the form. Fig. 53 shows a section on the line 53 125

of Fig. 52 and shows also the pinion which gears with the segments of teeth on this wheel. Fig. 54 is a detail view of this pinion. Figs. 55 to 58, inclusive, show the gear-surfaces of the wheels shown in Figs. 41, 45, and 49 developed, Fig. 55 showing the outer toothed and ribbed periphery of the wheel shown in Fig. 49, Fig. 56 showing the outer toothed and ribbed periphery of the wheel shown in Fig. 45, while Figs. 57 and 58 show, respectively, the outer and the inner toothed and ribbed portions of the wheel shown in Fig. 41. Fig. 59 is a diagram showing the gearing forming part of the mechanism for operating the bottom-nailing mechanism. Fig. 59^a is a diagram in perspective showing the gearing forming part of the mechanism for operating the bottom-nailing mechanism, the connections between the mechanism at the front and rear ends of the machine being shown. Fig. 60 is designed to illustrate particularly the manner in which the pinions that gear with the wheels shown in Figs. 41, 45, and 49 are formed with shoes having plane surfaces that engage the ribs or tracks on these wheels and prevent the pinions from turning except when positively actuated by the teeth on the wheels. Figs. 61 to 65, inclusive, are diagrams illustrating the manner in which the bands and body-blanks are applied to the form. Fig. 61 illustrates the position of the form when the bands are first applied to the ends thereof. This figure shows also part of the band-delivering and supporting mechanism. Fig. 62 illustrates the position of the form after it has been given a quarter-turn and the bands have been wrapped around it. Fig. 63 shows the same position of the form after the body-blanks have been bent about the form and the bands which are wrapped around it. Fig. 64 shows the position of the form after it has been given an additional one-half of a revolution and the bands have been wrapped completely around the body-blanks. When in this position, staples are driven at the sides of the basket. Fig. 65 shows the arrangement of the bands after the form has been given an additional one-quarter of a revolution, (thus completing a single revolution,) which will completely wrap the bands around the form and the body-blanks, and at this time the band-nailers operate to drive staples at the ends of the basket. Fig. 66 is a detail view, in horizontal section, illustrating particularly the novel devices which I employ for wrapping the bands around the form and the body-blanks, dotted lines indicating the positions of the mechanism after the form has been given one-fourth of a revolution. Fig. 67 shows a front elevation of the devices shown in Fig. 66. Figs. 68, 69, and 70 are detail views of a modified construction of part of the picker mechanism. Fig. 68 shows a front elevation of the picker-head with the front plate removed. Fig. 69 is a view similar to Fig. 68, showing some of the

parts in a different position, and this figure in addition shows a part of the mechanism for operating the devices carried by the picker-head. Fig. 70 shows an elevation of one end of the picker-head. Fig. 71 is a diagram showing in perspective parts of the band-feeding mechanism. Fig. 72 is a diagram showing in perspective parts of the blank carrying and bending mechanism. Fig. 73 is a diagram showing in perspective parts of the counting mechanism and the mechanism for feeding piles of blanks to the supply-wells below the pickers. Fig. 74 is a diagram showing parts of the nailing mechanism. Fig. 75 is a detail view of the nailing mechanism. 80

The main frame of the machine may be of any construction suitable to support the mechanism. In general, the frame consists of a front portion 1 and a rear portion 2, connected at the bottom by an angle-beam 3 and a double-angled beam 4. The front portion of the frame has a lateral projection on its left-hand side provided with a bracket 5, which supports the table 6, that carries the receptacles for the body-blanks and supports the pusher 90 that feeds piles of body-blanks to their receptacles. On its right-hand side the front portion of the frame is formed with a bracket 7 for supporting some of the mechanism and a shelf 8, to which the right-hand nailing mechanism is secured. The upper portion of the front frame has an upwardly extending and overhanging portion 10 and is provided with boxes for the vertical form-shaft and vertical shafts of the band-feeding screws. These 100 main parts of the frame are provided with suitable boxes or bearings for various parts of the mechanism and with brackets and shelves for supporting other parts thereof.

The main actuating-shaft 11 is arranged 105 horizontally and is mounted in suitable bearings in the front and rear walls of the main frame. Four large gear-wheels 12, 13, 14, and 15, (shown in Figs. 41, 45, 49, and 52,) which operate and control the movements of 110 the various parts of the machine, are bolted together and are attached to the rear portion of the shaft 11. They constitute what I call the "drum-gear."

The driving-shaft 16 is mounted in suitable 115 bearings on the right-hand side of the machine and carries a driving-pulley 17, which rotates in the direction indicated by the arrow in Fig. 3. The pulley is connected to the shaft by means of a clutch 18, operated by a lever 120 19, pivoted to a bracket 20 and jointed at 21 to an arm 22, secured to the rear end of a rod 23, that slides in suitable bearings and has jointed to its front end a handle 24. The connection of the rod with the handle is such as 125 to form a relatively short arm on the inner left-hand end of the handle, which has a flat surface that bears against a vertical wall of the shelf 8 when the handle is turned to the left and which thus causes the rod 23 to be 130

held in its forward position after it has been fully drawn forward. This movement of the rod uncouples the clutch, holding one member away from the other against the action of a spring 25. The handle is prevented from moving too far in one direction by a stop 26 on a rod 27, hereinafter referred to. The shaft 16 carries a pinion 28, which engages a pinion 29, rigidly connected with a pinion 30, turning on a short shaft 31 and meshing with a continuous annular series of teeth on the large gear-wheel 15, secured to the rear end of the main drum-gear shaft 11. In this way motion is imparted from the driving-shaft to the drum-gear shaft, and the shafts may be started and stopped promptly by means of the handle 24.

The body-blanks 500, from which the bottoms and sides of the baskets are formed, are contained in wells or receptacles 33 34 in the right-hand portion of the table 6. They are fed to these receptacles in the manner hereinafter described.

The die-carrier or crane 35, which carries the body-blanks from their receptacles to the form, consists of an arm 36, secured to a vertical shaft 37 and having on its outer end an annular frame 38, in which the die 39 is seated. The shaft is mounted in suitable bearings in the frame, in which it can revolve and also move vertically. A pitman 40 is jointed at one end to the arm 36 of the crane, and at its opposite end it is connected with an arm 42, projecting from a bar 43, that slides horizontally across the front of the machine in bearings at the right-hand side thereof. The connection between the pitman 40 and the crane is such as to permit the crane to move vertically relatively to the pitman, this connection, as shown, being effected by providing the arm 36 with a lug or bracket 41, carrying a vertical pin 44, which passes loosely through an eye in the end of the pitman and which is free to move vertically therein. The bar 43 carries an arm 45, to which is jointed one end of a connecting-rod 46, jointed at its opposite end to a crank 47 on the shaft 48, which carries a pinion 49, adapted to gear with teeth 50 and 51 on the large gear-wheel 13, (shown in Figs. 45 and 56,) the construction of which will be hereinafter more fully described.

Most of the parts above described are shown in diagram and in their organized relations in Fig. 72.

On the shaft 37 are mounted horizontally-projecting arms 52, between which is arranged a cam 53, secured to a shaft 54, which is mounted to revolve in suitable bearings, extends rearwardly, and carries a pinion 55, adapted to mesh with teeth 56 and 57 on the wheel 13. The arms 52 are connected together by a plate 58, but are loose on the shaft and do not revolve with it. As, however, the cam is revolved the arms are raised and lowered, and in rising the upper arm meets the under-

side of the crane and raises the crane and its shaft in such manner as to cause the body-blanks carried by the die to be bent around the form in the manner hereinafter explained. The arms 52 may be guided vertically in any suitable way.

The wheel 13, (shown in Figs. 45 and 46,) it will be observed, is equipped with teeth 50, 51, 56, and 57 for operating the pinions 49 and 55. It is also formed with ribs or tracks 59 and 60, which engage shoes 61 62 on the pinions and prevent the latter from rotating except when actuated positively by the teeth on the wheel, which latter are so disposed as to actuate the pinions 49 and 55 at the proper times to swing the crane and to raise and lower it.

Suitable mechanism for raising the body-blanks from their receptacles and depositing them in proper relation on the die is shown most clearly in Figs. 23 and 24. I would here say, however, that the picker mechanism shown in Figs. 68, 69, and 70 is preferred; but as that shown in Figs. 23 and 24 is simpler it has been shown as applied to the machine. The preferred mechanism will be described later. A bent bar or bracket 63 is secured adjustably in a sleeve 64 at the left-hand side of the main frame above the plane of the form, and on its downwardly-projecting arm it carries an adjustable collar 65, through which projects a horizontal rod 66, carrying at each end a vertical guide 67, provided with rollers 68, which guide a vertically-reciprocating rod 69, that I call the "picker-rod," and each of which carries on its lower end a head 70, equipped with needles 71. Preferably the bottom of each picker-head is concaved, as shown at Fig. 25, and this concaved portion connects by channels 72 with the outside to permit air to escape as the head descends upon the body-blanks and to allow the needles to better engage the blanks. The needles are clamped against the sides of the head by plates 73, which may be loosened and tightened for adjustment by means of bolts 74. Vertically-adjustable collars 75 are attached to the upper ends of the picker-rods, and under these collars are arranged the forked ends 76 of the arms 77, adjustably secured to a vertically-reciprocating rod 78, that has guides 79 80 at the upper and lower parts of the main frame. The rod 78 has secured to it a collar 81, to which is jointed one end of a link 82, the other end of which is jointed to a lever 83, pivoted at 84 to the main frame and carrying on the outer end of its shorter arm a roller 85, engaging a cam 86, secured to the drum gear-shaft 11. The arrangement is such that the picker-rods are raised by the cam 86; but the pickers drop by gravity. They can thus move downwardly independently of the arms 77 to any desired extent, being limited by the body-blanks on the top of the piles with which the picker-heads come in contact.

and the position of which varies as the piles of blanks lower during the construction of successive baskets. The arms move vertically to the same extent at each operation and always raise the pickers to the same elevation. The speed at which the pickers fall is governed by the shape of the cam 86, the part 87 of which is nearly radial, allowing the pickers to drop rapidly. The part 88 being on a tangent will cause the pickers to be raised slowly. While the roller 85 is on the part 89 of the cam the picker mechanism is inactive.

A rock-shaft 90 is mounted in bearings on the frame above the plane of the shaft 11, and to the rear end of this shaft is secured a finger 91, which hangs in the path of a pin 92, projecting horizontally forward from the front gear-wheel 12. To the front end of the shaft 90 is secured an arm 93, to the left end of which is jointed a collar 94, secured to a rod 95, that reciprocates vertically in guides 96 on a bracket 97, attached to the main frame. A spring 90^x, attached to the sleeve 64 and to the arm 93, holds the rock-shaft 90 and arm 93 in normal position and returns them to this position after they have been actuated by the pin 92. In order to prevent the rod 95 from turning, the collar 94 is formed with a guide-flange 98, that projects laterally into the space between one side of the bracket and a plate 99, attached thereto. On the lower end of the rod 95 is secured a cross-head 100, formed on its opposite ends with bosses 101, through which project and to which are adjustably secured the arms of a U-shaped wire frame 102, the outer end of which is bent down slightly, as shown in Fig. 23, in position to come in contact with a body-blank lifted from the well or receptacle 34. As the pin 92 travels forward it comes in contact with the finger 91 once in each revolution of the machine and through the mechanism before described causes the U-shaped frame 102 to come in contact with the body-blank carried by the adjacent picker-head, detach it therefrom, and deposit it on the die, which at this time is arranged below it.

The U-shaped frame just described constitutes what I call a "stripper," and it serves to cause a body-blank to be deposited upon another body-blank carried by the die in the manner hereinafter described. At the rear left-hand end of the table 6 is a post 103, to which is attached a horizontal rod 104, that supports a plate 105, (see Figs. 2 and 24,) having ears 106 at its upper end, through which the rod 104 extends and which are adapted to rock on said rod. A spring 107, attached to a collar 108 on the rod 104 and to one of the ears 106, holds the plate normally in a vertical position; but the plate is moved at times by a bolt 109, attached to the die-carrier. The ears 106 are perforated horizontally to receive the ends of a U-shaped stripper 421, similar to the stripper 102 and adapted to strip a

body-blank raised from the well or receptacle 33 by the picker that operates over it.

The above-described mechanism for raising and depositing the body-blanks is simple and efficient, and mechanism of this general construction has heretofore been employed by me. Occasionally, however, the pickers will fail to raise the blanks or will drop them prematurely. In Figs. 68, 69, and 70 I have shown improved devices which insure with absolute certainty that the blanks shall be raised and held until designedly detached and dropped upon the crane or die-carrier. The bar 430 corresponds with the vertically-reciprocating bar 69 in Fig. 23, and the arm 431 corresponds with the arm 77 in the same figure. The arm 431 is forked and extends under a collar 432, corresponding with the collar 75 in Fig. 23. The arm 431 may be operated in a manner similar to the arm 77 by a vertically-reciprocating rod 78 to raise the bar 430 and allow it to fall in the manner before described.

The lower end of the bar 430 is chamfered or cut away at opposite sides to form a straight portion 433 and inclined surfaces 434, joining the portion 433, with the wider part of the bar above it. The part 433 is formed with a slot 435, through which passes a bolt 436, that also extends through two parallel vertical plates 437 and serves to lightly grip the plates 95 against the bar. The plates are of the required form to provide bearings for two parallel cross-pins 438, on which are journaled to swing two levers 439, and the lower portions of the plates are formed to present extended flat surfaces which strike squarely against the body-blanks of the basket when the picker descends. The plates are formed on their inner sides with vertical ribs 440 for guiding the picker-bar when it moves relatively to the plates and for preventing the plates from swinging about the bolt 436. The levers 439 have upwardly-extending inwardly-curved arms, which at certain times ride up and down on the inclines 434. When the upper ends of the long arms of the levers ride up the inclines, they are thrown outward, causing the lower shorter arms of the levers to be moved with considerable force inward toward each other. These shorter arms of the levers are curved outwardly and are formed at their lower ends with presser-feet 441, that extend across the picker-head from one plate 437 to the other, and their lower surfaces are arranged to come into the same horizontal plane with the bottom of the plates when they are moved inward and downward to their full extent by the engagement of the upper ends of the levers with the inclines 434. Needles 442, carried by each presser-foot, are arranged tangent to a circle of which the fulcrum-pin 438 constitutes the center, so that as the presser-feet are swung inward and downward the needles are pressed approximately straight through or into the top blank of the pile, but

at acute angles of, say, thirty degrees from the horizontal plane of the upper face of the blank. The needles are secured to the presser-feet by clamping-bars 443, bolted to the outer upwardly-inclined ends of the presser-feet. The depth of penetration may readily be adjusted by these devices.

Projecting from opposite sides of the lower end of the bar 430 are lugs 444, which are 10 adapted to come in contact with the lower arms of the levers just below their pivots whenever the bar is moved upwardly or whenever the bar is held stationary, and the plates carrying the levers are pushed downward, as 15 is the case when the plates are operated on by the wiper 445, attached to a rod 95, like that shown in Fig. 23. At this time the plates are moved downward relatively to the picker-bar until the upper ends of the levers leave the 20 wider upper portion of the bar and their lower ends come in contact with the lugs 444, which causes the levers to swing on their pivots, withdrawing the needles from the blank and causing their ends or points to rise to a level 25 with the bottoms of the plates.

Fig. 68 shows the positions of the parts when the picker is raised. When it drops or is moved downward, the plates 437 first strike the upper blank of the pile, and as there is 30 more or less friction exerted between the bar and the plates the blanks are pressed in such manner as to be flattened out, and thus held under pressure during the further downward movement of the picker-bar, which as it descends actuates the levers in such manner as 35 to move the needles diagonally into the upper blank of the pile in the manner illustrated in Fig. 69, which latter figure shows by dotted lines a blank engaged by the needles. 40 When the picker rises, the parts all maintain for a time the relative positions shown in Fig. 69, there being sufficient friction exerted between the plates and the bar owing to the clamping action of the bolt 436. In this 45 way a blank is lifted to a position over the horizontal plane in which the crane or die-carrier moves and just below the end of the wiper 445, which at the proper time engages the upper end of the plates 437. This wiper may 50 be actuated by mechanism similar to that used to actuate the wiper 102. (See Fig. 23.) In the present case, however, the wiper is actuated when the picker-bar is stationary and causes the plates and levers to move downward until the blank comes within the guide-posts 117 on the crane. At this time the lugs 444 come in contact with the levers 439 and cause the needles to be withdrawn from the blank, which then drops into the proper position 55 on the die. This leaves the different parts of the picker in the position shown in Fig. 68, ready to descend on the blanks at the next operation.

It is obvious that the blank cannot become 60 detached from the picker accidentally. This

can only be done by a positive actuation of the needle-carrying levers.

The die-carrier or crane, as before explained, carries two body-blanks from the receptacles 33 and 34 to the form for the construction of each basket. 70

The die upon which the blanks are deposited by the pickers in its simplest form is shown in Figs. 5 and 6. The frame of this die has a vertical rectangular opening of the 75 general size and shape of the outside of the basket to be formed and two circular flanges 110 and 111, adapted to bear, respectively, on the top and inner side of the annular frame 38 of the crane. The die is at times locked to 80 the crane by means of a bolt 112, that slides through the wall of the frame 38 and through an aperture 113 in the flange 111. The bolt is drawn in one direction by a spring 114, and it is moved at times in the opposite direction 85 by a bell-crank lever 115, connected with a rod 116, moving vertically in the arm 36 of the same, and adapted to come in contact with the frame of the machine as the crane is raised, the arrangement being such that as soon as 90 the crane is raised the die is unlocked and is free to revolve with the form when it is engaged therewith. Upwardly-projecting fingers 117 on the crane of the kind shown in my patent of August 6, 1901, are employed 95 to center the blanks.

A rigid die, such as shown in Figs. 5 and 6, has a slight drawing action on the body-blanks while they are being bent. In order to remedy this, I may construct the die in the manner shown in Figs. 7 to 11, inclusive, in which the construction is such as to apply pressure gradually to the blanks while they are being bent. The die is formed with an annular depending flange, fitting the annular frame 38 of the crane, and a flange that rests on the top of said annular frame, being similar in this respect to the die shown in Figs. 5 and 6. The die is formed with a vertical opening, inside of which is arranged a plate 118, having a vertical opening and carrying four leaves 119, which are hinged to the plate in such manner as to lie even therewith when the plate is in its elevated position, as shown in Fig. 8. To the under sides of the leaves are jointed 110 links 120, which are arranged in recesses of the die and are pivoted at their lower ends to said frame within said recesses. The plate 118 and the leaves 119 are pressed upward and normally held in the position shown in Fig. 8 by springs 121, the inner ends of which engage the under side of the plate and the outer ends of which are coiled around rods 122, suitably mounted in the under side of the die. The arrangement is such that when carrying 115 body-blanks from the receptacles to position under the form the blanks will rest on the frame 118 and the leaves 119 when they are in the position shown in Fig. 8; but when the crane is raised the form (which does not en- 120

gage the leaves) will cause the plate 118 to be depressed into the die while the latter is rising, thereby causing the leaves to be turned to the position shown in Fig. 10, in so doing bending the blanks with a yielding pressure around the form as the latter enters the die. A die having its walls collapsible or made to gradually yield, as above described, is found to be very efficient in action, especially when the blanks are scored at their bending-lines, as is now commonly the case.

In carrying body-blanks from the receptacles to the form the crane first holds for an instant the die over the receptacle 33 and receives a blank from the picker above it, then moves to the receptacle 34 and receives a blank from the picker above this receptacle. It will be observed by reference to Fig. 3 that these receptacles are arranged at an angle to each other, the angle being such that after a body-blank taken from the receptacle 33 has been placed by the stripper 421 on the die and the die moved over to the receptacle 34 the body-blank on the die will be arranged crosswise or at right angles to the body-blank held over the receptacle 34 by the picker. The wiper 102 detaches the blank from the picker and deposits it crosswise of the blank on the die in the manner before described, and after the two blanks have been thus arranged the crane is moved into position beneath the form 123, the construction and operation of which will be next described.

Fig. 56 clearly illustrates the arrangement of teeth and tracks on the wheel 13, and Fig. 60 shows how the shoes on the pinions are formed. Other figures merely show the outlines of the shoes, which in some cases are different in detail from that shown in Fig. 60; but their construction will readily be understood without further illustration. These shoes for holding the pinions steady when not positively actuated have heretofore been employed by me and are shown in several of my prior patents. I will hereinafter call them "steadyng-shoes." The construction of the wheel 13 is such that in one revolution thereof the crane is moved from its position over the pile of blanks to a position under the form. It then pauses for a short time, is then raised to bend the body-blanks around the form, then pauses again, and after this it is lowered and swings to a position over the receptacle 33, reverses, and then swings back to a position over the receptacle 34, where it again pauses. These movements of the crane can readily be traced by a consideration of the movements which will be given to the pinions 49 and 55 by the wheel 13 when revolving in the direction indicated by the arrow in Fig. 45.

The form is shown most clearly in Figs. 15 to 18, inclusive. It is of approximately the size and shape of the inside of a basket, being hollow and closed on the bottom and its four sides.

At intervals around its upper edge it is provided with hardened clinch-plates 124 of well-known construction, and it is formed with a central hub 125, into which the form-shaft extends and to which it is secured. At two of its diagonally opposite upper corners the form is provided with hooks 126 to receive the bands hereinafter more particularly referred to. The outer ends of the hooks are in line with the straight upper walls of the smaller ends of the form, which latter are recessed or slightly beveled or inclined near the hooks to allow the ends of the bands to be slightly bent as the form revolves, so that when the form is revolved to a sufficient extent to wrap the bands around the outside of the hooks the bands will lie straight across the ends of the form. Horizontally-arranged grip-bars 127 are arranged to slide along the inner side walls of the form, being guided by the internal webs 128 thereof, and to pass through openings in the end walls of the form. When moved outward, these bars grip the ends of the bands in the hooks, the latter being thus firmly held as the form revolves. The grip-bars are jointed to a centrally-pivoted lever 129, and one of said bars is connected to one end of a lever 130, pivoted at one end to the form. A spring connected to the lever 129 and to the form tends to withdraw the grip-bars away from the hooks. A lug 131 projects upwardly from the lever 130 and bears against the periphery of a ring 132, adjustably secured, by means of bolts 133, to the under side of the lower box 134, in which the form-shaft is journaled. The ring is formed with a recess 135 in its periphery, into which the lug 131 at times projects. While the form is revolving and the lug is outside the recess the grip-bars hold the bands in the hooks; but after the form has made a complete revolution the lug enters the recess and allows the grip-bars to retreat, make room for new bands, and allow the completed basket to be ejected. 130 indicates a clinch-plate arranged centrally in the bottom of the form to receive the bottom staple.

The form-shaft 136 is free to turn and to move vertically in its boxes 134 and 137. It carries a bevel-pinion 138, resting on the box 134 and attached to the shaft 136 by a feather-and-groove connection, permitting the shaft to move vertically without moving the pinion, which latter gears with a bevel-pinion 139 on a horizontal shaft 140, that carries on its rear end a pinion 141, gearing with teeth 142 143 144 on the gear-wheel 12. (See Fig. 71.) The pinion 138 has, however, twice as many teeth as the pinion 139, and the pinion 141 has six teeth gearing with the three sets of teeth 142 143 144, there being three teeth in each set 142 143 and six teeth in the set 144. By this arrangement the pinion 141 is given a one-half revolution by the teeth 142 and 143 and a complete revolution by the 130

teeth 144. The teeth 142 and 143 thus give a one-fourth revolution to the form, while the teeth 144 give a one-half revolution thereto, there being an interval of rest between each 5 movement. The pinion 141 is formed with a shoe 145, having flat faces to engage a sectional track 146 on the periphery of the wheel 12 on opposite sides of the teeth, by which arrangement the pinion is prevented from 10 moving except when moved positively by the teeth 142, 143, and 144.

The form is raised and lowered as follows: The upper end of the form-shaft extends through a sleeve 147, on opposite sides of 15 which are collars 148, attached to the shaft. This sleeve is formed with a sleeved extension 149, through which extends a vertical guide-rod 150, attached to the frame, and an arm 151, extending laterally and downwardly 20 from the sleeve 149, is jointed to a pitman 152, in turn jointed at its lower end to a crank 153 on a horizontal shaft 154, which carries on its rear end a pinion 155, meshing with teeth 156 on the wheel 12. The pinion 155 has six 25 teeth and meshes once during each revolution of the wheel 12 with the six teeth 156 thereon. By this mechanism the form is depressed to deliver a completed basket and is immediately raised. The pinion 155 is provided 30 with a steadyng-shoe 157, engaging a track 158 on the wheel 12. The teeth 156 are so located on the wheel 12 as to lower and raise the form just after the form has been given a full revolution and a basket has been completed. 35

The bands 501 are arranged in piles on opposite sides of the form, their inner ends being located just above the plane of the form, while their outer ends are supported by the 40 frames 160 and 161. The frame 160 to the right of the form and in front of the machine consists of a rod 27, attached to the main frame, projecting forwardly therefrom and carrying near its outer end an adjustable collar 163, to which is adjustably secured a vertical rod 164, bent at its upper end to form a 45 downwardly-extending U-shaped portion 165, adapted to receive the outer ends of the bands. The pile of bands rest on an adjustable block 50 166 some distance above the bottom of the U-shaped portion 165, the arrangement being such that the bottom band may be given a quarter-turn and delivered to the bottom of the frame in proper position to be wrapped around the form. The bands on the left-hand side of the form are supported in a similar manner, except that they extend rearwardly, and the frame 161 is adjustably secured to a collar 167, attached to the bracket 63. 55

60 The inner ends of the bands are arranged in vertical chambers formed between the screw-shafts 168 and the vertical plates 169 and 170, the latter constituting gages for the ends of the bands. The shafts 168 are mounted to revolve in suitable bearings formed in 65

brackets 171, projecting from the overhanging front portion of the main frame, and the lower end of the plates 169 and 170 are attached to brackets of the main frame in any suitable way, the preferred arrangement being 70 clearly shown in the drawings. (See Figs. 21 and 22.) The shafts 168 are geared to the form-shaft 136, and motion imparted to the form-shaft will be communicated to the shafts 168.

The feed-screws 173 and the band-ejecting 75 cams 195 are similar to those shown in my patent of August 6, 1901, and they operate in a similar way, feeding the bands one at a time downwardly, turning them up edgewise through which they are moved downward by the four band-plungers 175 176 177 178. (See Fig. 71.) Weights 422, sliding vertically on the shafts 168, rest on the piles of bands and press them downward into engagement with the screws. These weights may be raised to the desired extent when it is necessary to supply additional bands to the machine. The band-plungers are hinged to a cross-head 180, that slides vertically on the 80 form-shaft. The cross-head is formed on its rear side with a horizontal groove 181, which receives a roller 182 on a crank-wheel 183, secured to the front end of a shaft 184, carrying a pinion 185, meshing with an intermediate pinion 187 on a shaft 188, driven by a pinion 189, fixed on the front end of a short shaft 190, turning in a long box and having on its rear end a pinion 192, that is driven by the teeth 156 on the wheel 12, which same 85 teeth it will be remembered serve to raise and lower the form. The pinion is also provided with a steadyng-shoe 193, that engages the track 158. The plungers are moved downward while the form is rising. 90

The band-plungers are formed at their lower ends in such manner as to engage the bands after they have been turned up edgewise and delivered to the upper ends of the channel 174. There is a pair of band-plungers on each 95 end of the cross-head 180. One band-plunger of each pair is formed on its lower end in such manner as to engage the end of the band close to one of the hooks 126, as illustrated in Fig. 61, and to move it into engagement with the 100 hook, while the other plunger, 176 or 178, of each pair is formed with a hook 194, which engages the band just outside the circle traveled by the corners of the form as the form 105 revolves. The plungers remain down while the form is revolving and while the ejector-cams are pushing other bands into the channels 174, so that when raising the plungers it is necessary that they should be swung clear of these bands in the channels. This is accomplished as follows: The hub 196 of each 110 pair of plungers is formed with a lug 197, entering a recess 198 in the upper end of a friction-plate 199, which is pressed against the plate 169 by a spring-actuated lever 200, car- 115

rying a friction-roller 201. As the plungers are raised the lugs will be first turned by the plates 199, which for a short time remain stationary in the manner illustrated in Fig. 20, 5 causing the lower ends of the plungers to swing inward and be held there until the ends of the plungers have cleared the bands in the channels, then the plates will rise with the plungers. When the plungers move downward, they will be moved back to the vertical position in a similar way.

Plates 202 203 are attached to the brackets below the band-screws and serve to guide the bands into hooks 204 205, the construction and 15 operation of which will next be described.

A spur-gear 450 is rigidly connected with the bevel-gear 138 and meshes with a pinion 451, revolving on a stud 452 on an arm 453, projecting from one of the plates 169. The 20 pinion 451 carries on its upper side a crank-pin 454, to which is jointed one end of a link 455, the opposite end of which is jointed to a collar 456, adjustably secured to the horizontal shank of the front band-hook 204. The 25 shanks of the band-hooks 204 205 are adjustably secured to an oblong block 457, which is loose on the form-shaft and rests on the spur-gear 450. The shanks project from the diagonally opposite corners of the block and are 30 then bent at right angles in a horizontal plane and are then turned downward in such manner as to hold their hooked portions near those diagonally opposite corners of the form which are not provided with the hooks 126. The 35 hooks 458 are adapted to receive the bands as they are fed from the band-receptacles and to hold them in proper positions to be wrapped around the form as the operation of forming the basket proceeds and to give such tension 40 to the bands as will hold them against the sides of the form and prevent them from twisting or buckling. Each hook is provided with a spring 459, which serves to press on the bands and hold them with sufficient security in the 45 hook. As a band descends into the hook the spring is put under tension, the latter being adjustable by means of a set-screw 460. The arrangement is such that the gear 450 revolves with the form and the pinion 451 is 50 given two revolutions to one of the gear 450, so that as soon as the form has been given one-fourth of a complete revolution, moving to the position shown by dotted lines in Fig. 66, the pinion 451 will have been given one-half of a revolution and the band-hooks will 55 have been swung in a direction opposite to that of the movement of the form into the positions shown by dotted lines in Fig. 66. In so doing the hooks pass to those corners of 60 the form where the hooks 126 are located and cause the bands to lie against the two long edges of the form. If the hooks did not move in this way, the bands would not be brought properly into engagement with the form along 65 its two long sides, but would be held dia-

nally away from them. As the form is given another quarter-turn the pinion 451 will be given one-half of a revolution (thus completing a full revolution) and the hooks will travel in the same direction as the form; but 70 will continue to pull gently on the bands, because the distance traveled by the hooks is less than that traveled by the edge of the form in the same time, this distance being approximately the length of one end of the form. 75 The movements above described are repeated during the remaining two quarter-turns given to the form, which complete the formation of the basket.

The wires 502 for forming the staples or 80 nails for attaching the bands to the body-blanks are fed from reels 206 by means of feed-rollers 208 and 209. Four wires are employed and two staples are formed and driven by the nailing mechanism on each side of the 85 machine at each operation. The rollers 208 are secured to the opposite ends of a shaft 210, which extends horizontally across the front of the machine and is mounted to revolve in suitable bearings in the upper portion thereof. The shaft 210 carries a ratchet-wheel 211, 90 engaged by a pawl 212, pivoted to the upper end of a bar 213, that reciprocates vertically in suitable guides in the frame and is engaged by one arm of a bell-crank lever 214, pivoted 95 at 215 to the main frame, and carrying on its other arm an adjustable pin 216, that engages a cam 217, forming part of the nailing mechanism on one side of the machine hereinafter described.

There are two grooved feed-rollers 208 on each end of the shaft 210, and these coöperate with a like number of rollers 209, each one of which is journaled independently on a fixed stud 218 on the lower end of a lever 219, pivoted independently on a bracket 220, projecting from the front frame. The rollers 208 and 209 are provided with gears that intermesh, so that as the shaft 210 is revolved all the rollers 208 and 209 will revolve with it. 105 Each of the levers 219 has secured to its upper end a spring 221, which draws the roller 209 into engagement with the corresponding roller 208. Each spring is connected with a pulling-rod 222, which extends into the 110 spring and is attached thereto by a cross-pin 223. The pulling-rod is bent downwardly and is jointed to the shorter end of a bell-crank lever 425, pivoted to a projection of the main frame and having its lower end suitably formed 115 to provide a handle. The arrangement which is shown in Fig. 14 is such that when the handle is in the position shown by full lines in Fig. 14 the spring will exert the required pull on the lever 219 to cause the roller 209 to bear against the roller 208 with the desired pressure; but by turning the lever 425 to the 120 position shown by dotted lines in Fig. 14 the joint of the lever with the pulling-rod is moved toward the upper end of the lever 219, 125

thereby relaxing the tension of the spring and pushing the lever to the dotted position, thus withdrawing the roller 209 from the roller 208. It is obvious that the parts will remain 5 in this condition until the handle is turned down to draw the front end of the pulling-rod forward and to a point below the pivot of the handle.

In order to uncouple the wire-feeding rollers at any time, the operator may pull forward the handle 225, which is formed on a 10 rod 226, pivotally attached to the upwardly-projecting end of the pawl 212. The rod 226 extends through an opening in the frame and 15 has a shoulder 227, adapted to engage the frame at the front of the opening. The rod has a rearwardly-projecting portion 228, to which is attached a spring 229, also attached to a lug 230 on the upper rear end of the bar 20 213. The arrangement is such that the spring 229 normally holds the pawl in engagement with the ratchet-wheel; but when the handle 225 is drawn forward and the shoulder 227 25 engages the frame the spring will draw the shoulder against the frame and hold the handle steady even while the bar 213 is reciprocating, and the pawl will be disengaged from the ratchet.

Any one of the wire-feeding rollers 209 may 30 be thrown out of action independently of the others by means of its handle 225, while all the sets of wire-feeding devices may be simultaneously thrown out of action by means of the handle 425.

35 Two wires 502 are fed to the nailing mechanism on the right-hand side of the form and two wires are fed to the nailing mechanism on the left-hand side thereof. Guide-tubes 261 may be provided for directing the wires from 40 the feed-rollers to the nailers. The two nailers 231 232 are of the same construction and operate in the same way. (See Fig. 74.) The bases 233 of the nailers are secured to the main frame and occupy the positions shown 45 in Fig. 1. At its end next the form the base 233 of each nailing is formed with a forwardly-projecting upper portion 234, while the opposite end of each base has secured to it a bracket 235, having guides for the hammer- 50 rods 236, which extend into sleeves or staple-formers 237, that slide in bearings in the portion 234 of the nailing-frame. The hammers 238 are secured to the ends of the hammer-rods inside the staple-formers, and they are 55 secured by cross-pins 239 to collars 240, arranged loosely within openings in the cross-head 241, which carries the rods. One end of each opening is closed by a screw-plug 242, fastened to the cross-head, and between each 60 screw-plug and a collar 240 is interposed a spring 243. The hammer-rods are connected to the staple-formers by slot-and-pin connections 245, so arranged that the hammers may have a limited movement forward independ- 65 ently of the staple-formers; but on the re-

turn stroke after having driven a staple each hammer-rod by reason of this slot-and-pin connection will after having moved for a short time independently cause the staple-former to be moved back to its normal position. The 70 cross-head 241 has attached to it a pitman 248, which is operated in the manner herein-after described. Collars 244 are adjustably secured to the hammer-rods close to the plugs 242, the arrangement being such that when 75 the cross-head retreats from the form the plugs will engage the collars and cause the hammer-rods to retreat. The staple-formers are carried by a cross-head 246, between which and the cross-head 241 are interposed springs 80 247, that encircle the hammer-rods and are somewhat weaker than the springs 243. The cross-head 241 carries a pawl 249, which engages the cross-head 246 and has a short arm 250 extending into a channel or groove 251 85 in the base 233. When the cross-head 241 moves forward toward the form, the hammers and staple-formers are first moved together; but as soon as the arm 250 strikes the end 252 of the channel the pawl 249 is disengaged 90 from the cross-head 246 and the hammers move forward, while the staple-formers soon come to rest, their inner ends then resting against the basket under construction. The hammers move a short distance forward 95 independently of the staple-formers against the force of the springs 247. The front end of each staple-former is provided with a cylindrical block 253, centrally bored to allow the hammer to pass through it and having grooves 100 254 for the sides of the staples. Each staple-former carries a knife 255, coöperating with a stationary knife 256, and an anvil 257 is arranged to slide across the mouth of the opening in the portion 234 of the nailing-frame. 105 The front end of each staple-former is slotted at 260 to receive the anvil, and the block 253 is correspondingly slotted. Each anvil is pressed inward by a spring 258 and is moved outward by the inclined end of a bar 259, 110 adjustably secured to the cross-head 246. As the cross-head 242 moves forward the staple-formers are correspondingly moved. The knives sever lengths of wire, and these are bent around the anvils and remain in the 115 openings of the blocks 253. As soon as this occurs the pawl 249 is disengaged from the cross-head 246; but the staple-formers continue to move forward by reason of the connection between the cross-heads 242 and 246 120 afforded by the springs 247. As soon as the ends of the staple-formers come against the bands of the basket under construction they stop moving, while the hammers continue to move in and press the staples into the bands. 125 The springs 243 are, as before stated, somewhat stronger than the springs 247 and are not always put under compression; but should there be any variation in the stock used to construct the basket they will yield to accom- 130

modate this irregularity. The hammers are formed with ribs 262, fitting the grooves 254 in the blocks 253.

The pitman 248 of the right-hand nailer is connected to the upper end of an upright oscillating lever 263, pivoted at the right-hand end of the front of the machine. To the upper end of the lever 263 is also connected one end of a pitman 264, the opposite end of which is jointed to a crank-pin 265 on the nailer driving mechanism. (Shown in Figs. 33, 34, and 35 and also in Figs. 74 and 75.) The crank-pin is attached to an eccentric-strap 266, encircling an eccentric 267, secured to the end 15 of a shaft 268, extending through a sleeve 269, that carries on one end a crank-arm 270, having a radial slot 271, into which a stud on the crank-pin carrying a roller 272 projects. The rear end of the shaft 268 carries a pinion 273, and the rear end of the sleeve carries a pinion 274. The shaft is free to revolve in the sleeve, and the sleeve is mounted to revolve in suitable bearings in the main frame.

Each pinion 273 274 has six teeth and a steadyng-shoe 275 276 with a plane flat surface. These pinions are adapted to gear with teeth 277 278 inside the rim of the wheel 12, Figs. 41 and 58. Plane track-surfaces 279 280 are arranged on opposite sides of the teeth on 30 the wheel and engage the shoes 275 276 to prevent the pinions from rotating except when positively moved. When the pinion 274 revolves, the crank-arm will correspondingly revolve and will carry with it the crank-pin, 35 and when the pinion 273 is turned the eccentric will be turned in such manner as to move the crank-pin either in or out radially. The pinion 273 engages the series of teeth 277, while the pinion 274 engages the teeth 278.

40 In the operation of the machine the tooth 281 of the series 277 first engages the tooth 282 (see Fig. 41) of the pinion 274, and the crank-arm and crank-pin are moved from the normal position shown in the drawings up to 45 the horizontal position, (shown in Figs. 41 and 48,) which is the position of outstroke of the crank-pin. At this time the next tooth 283 engages the pinion 274, and as the same tooth engages the pinion 273 both pinions revolve together, and as long as the teeth 277 and 278 coincide they carry the pinions 273 and 274 around one revolution, together with the crank, in a fixed radial position, traversing the larger circle 284. (Shown in Fig. 48.) As soon as 55 this is accomplished the pinion 273 passes out of gear with the teeth 278 and the shaft 268 ceases to rotate, while the pinion 274 and the crank continue to rotate, and as the eccentric is stationary the crank is caused to be moved 60 in radially and to describe the smaller circle 285 in Fig. 48. By this arrangement the pitman 264 is given alternately a long and a short stroke, and thus the nailings-hammers and staple-formers are moved with a long stroke in 65 toward the axis of the form when nailings at

the sides of the basket and then are driven a shorter distance when nailings at the ends of the basket.

The gearing on the wheel 12 is such that when the nailers first operate the body-blanks and bands are arranged as shown in Fig. 64, the nailers being given a long stroke. Then the form is given a one-fourth revolution, the bands and the body blanks being then arranged as shown in Fig. 65, at which time the nailers are given a short stroke and the staples are driven at the ends of the basket.

The lower end of the oscillating lever 263 is connected by a rod 286 with a horizontal oscillating lever 287, provided with a segment 80 of teeth meshing with a segment of teeth on a vertically-arranged oscillating lever 288 on the left-hand end of the table 6. The upper end of this lever is jointed to the pitman 289 of the left-hand nailing mechanism. By this 85 arrangement both nailers are driven from the same crank-pin and both are given a long and a short stroke alternately, as before described.

Beneath the form is arranged a basket-receiving chute 290, into which the completed 90 baskets are delivered and stacked or nested one within the other as rapidly as they are made. After a predetermined number has been thus stacked the baskets are automatically discharged from the chute in the manner 95 hereinafter described. It is desirable that the body-blanks should be secured together by a nail or staple driven centrally through the bottom of the blanks after they are crossed. The nailing mechanism for this purpose is attached to the chute, which latter is mounted 100 to move laterally or horizontally toward and from the form, so as to alternately bring the mouth of the chute and the top of the nailings mechanism beneath the form.

The chute has a rear wall 291, a bottom 292, and a front wall 293, the right and left hand ends being for the most part open. Near the top the front and rear walls are connected at the left-hand side by a plate 294, which is 110 provided with lugs 295, in which is secured a rod 296, to which are pivotally connected two hooks 297, the upper ends of which are pressed inward by springs engaging the lower ends of the hooks below the rod 296. These hooks 115 engage the basket when it is moved into the chute by the downward movement of the form, and when the form moves upwardly they, in connection with the hooks 298, strip the baskets from the form. The hook 298 is 120 pivoted at its lower end to the rear side of the rear wall of the chute, and at its upper end it is bent laterally away from the chute, the outer end of this bent portion being provided with an arm 299, adapted to engage the top 125 of the basket on one end. By this arrangement the column of completed baskets may be moved out of the chute beneath the arm 299. The spring 300, attached to the upper end of the hook 298 and to the wall of the 130

chute, serves to pull the hook inward, but allows it to move outward when a basket is being delivered to the chute by the form. The hooks 297 and 298 thus act automatically to strip the completed baskets from the form as the latter descends. The hooks first recede laterally and then move inward and engage the upper edge of the basket at its two ends. Then as the form recedes the basket is detached by the hooks and finally falls into the chute and is nested in the basket below it. A bent rod 301, attached to the rib 302 on the rear side of the rear wall of the chute, limits the outward movement of the hook 298.

15 Near the bottom of the rear wall of the chute are two boxes 303, to which are secured two rods 304 305, that are mounted to slide back and forth in boxes in the lower part of the main frame. The rod 305 merely serves 20 as a guide to cause the chute to move evenly back and forth. The rod 304 extends to the rear end of the machine, and to this rod, about midway between its ends, is secured a collar 306, having a laterally-projecting arm 307, to 25 which is jointed a pitman 308, connected with a crank 309 on the lower end of a vertical shaft 310, on the upper end of which is a bevel-pinion 311, having a shoe 312 and engaging tracks and teeth 313 314 on the rear wheel 15 30 of the drum-gear. (See Figs. 52 and 53.) The teeth and tracks 314 and 313 are formed on a ring 315, bolted to the side of the wheel 15. The pinion 311 has twelve teeth, and each series of teeth 314 has six teeth. Each 35 series thus gives a one-half revolution to the shaft 310, with a pause between each half-revolution. A one-half revolution given to the pinion 311 by one of the series of teeth moves the chute outward, while a half-revolution given to the pinion by the other series moves the chute inward. As shown in the drawings the chute is just ready to begin its outward movement.

40 The mechanism for forming and driving a staple into the bottom of a basket is, as before stated, carried by the chute. The rear wall of the chute has a rearwardly-projecting portion 316 at its upper end, which is formed with a vertical groove or channel 317, in 45 which slides a staple-forming sleeve 318, rectangular in cross-section and the lower end of which is formed with a bored-out chamber 319 to receive a hammer-rod 320, to the upper end of which is secured a hammer 321, fitted to move vertically in a groove 322, 50 formed in the wall of the sleeve and extending from its upper end downwardly to the bored opening or chamber 319, in which latter is arranged a spring 323, that encircles the 55 hammer and bears against the upper end of the hammer-rod and the top wall of the chamber. The hammer-rod is connected to the sleeve by a pin 324, which is secured to the rod and passes into a slot 325 of the sleeve, by 60 which arrangement the hammer-rod is per-

mitted to move a slight distance independently of the sleeve while driving a staple and when being withdrawn after the staple is driven. The staple-forming sleeve is held in its guide-channel by a cap 326, which is formed with two arms 327 for guiding the upper end of the anvil-carrying rod 328, the lower end of which is adjustably attached to a split sleeve 329, having a laterally-projecting arm 330, hinged between a lug 331, projecting 70 from the rear wall of the chute and the adjacent side wall of the portion 316 of the chute. The lower end of the rod 328 is pressed outward by a spring 332, causing its upper anvil-carrying end to be moved inward to present 75 the anvil at the proper time to the wire-bending mechanism. The anvil projects into the groove 322 and has laterally-projecting side lugs 333, provided with inclined surfaces that engage at times the curved faces 334 on the 80 top of the staple-forming sleeve. This construction enables the sleeve to push the anvil to one side after the staple has been formed and while it is being advanced to the basket and the hammer is advancing to drive the staple. At this time the inner end of the anvil moves downwardly in the groove 322, while the lugs 333 ride along the outside of the sleeve. The lower end of the hammer-rod is guided vertically by a box 335, and above 85 this box is a collar 336, which is secured to the hammer-rod and has a laterally-extending arm 337, provided with a horizontally-grooved channel 338, in which travels a roller 339, carried by a pin projecting from the 90 front end of a disk 340, which latter is driven in the manner hereinafter described. The collar 336 is formed with lugs 341, to which is pivoted a pawl 342, having near its upper 95 end a shoulder 343, that engages the lower 100 end of the staple-forming sleeve, and also a top portion 344, that rests on the sleeve. The extreme upper end of the pawl is beveled and is adapted to come in contact with a beveled lug 345, projecting from the lower end 105 of the cap-plate 326. As the hammer-rod is raised vertically the staple-forming sleeve is raised by means of the pawl attached to the hammer-rod; but as soon as the upper beveled end of the pawl engages the lug 345 the 110 pawl is detached from the sleeve, which at this time comes in contact with the basket-blanks. The hammer-rod continues to move vertically, and the sleeve is held with a yielding pressure against the body-blanks of the 115 basket. After the staple is driven the hammer retreats, the sleeve being held in proper position on the hammer until again engaged by the pawl 342 in the manner before described. The slot-and-pin connection between 120 the hammer-rod and the sleeve prevents the hammer-rod from being withdrawn to too great an extent from the sleeve. A spring 346, carried by the collar 336, engages the 125 lower end of the pawl 342 below its pivot 130

and serves to keep the pawl engaged with the sleeve at the proper time.

The upper end of the channel in the sleeve is formed with grooves 347 to receive the side wires of the staple after they are bent, and the hammer is formed with ribs 348 fitting the grooves. The wire is fed through a hardened tube 349 above the staple-forming sleeve and to one side thereof and which delivers the wire across the top of the sleeve, which latter carries a cutter 350, coöperating with the end of the tube to sever proper lengths of wire. When in the position shown in Fig. 39, the mechanism is just ready to form a staple. As the sleeve moves upward a length of wire is severed and is pressed against the under side of the anvil and bent around it. Then the anvil recedes laterally and the staple is received into the grooves 347. The top end of the staple-forming sleeve then rests against the basket-blanks, and the hammer advances (moving independently of the sleeve) and drives the staple into the blanks. After the staple is thus driven the hammer retreats into the sleeve, and then the hammer and sleeve move downwardly together, and the anvil moves back into position above the sleeve.

The disk 340 is attached to the front end of the shaft 351, that has bearings at its front end in a box 352, on a bracket 353, attached to the rear side of the rear wall of the chute, and at its rear end this shaft has bearings in a box 354, attached to the front portion of the machine. The shaft is mounted to both reciprocate and rotate in the boxes. The reciprocating movement of the shaft 351 is caused by the back-and-forth movement of the chute, while the rotary movement is given to the shaft by a pinion 355, meshing with a segmental series of teeth 356 on a wheel 357, fixed to the shaft 54. The wheel 357 is formed with a track 358, that engages a shoe on the pinion 355 and prevents it from rotating except when positively moved by the teeth 356. As the shaft 54 has only a half-revolution given to it when the crane is being raised and only a half-revolution when being lowered, as before described, the pinion 355, and consequently the disk 340, will be given one revolution during that half-revolution of the shaft 54 in which the crane is being raised, it being remembered that there are a sufficient number of teeth in the semicircular segment 356 to give a complete revolution to the pinion 355, and this segment engages the pinion 355 at a time when both series of teeth 56, 57 are out of gear with the pinion 55. During that half-revolution of the shaft 54 when the die is being lowered the disk will be held stationary, as at that time the track 358 engages the steadyng-shoe on the pinion 355. Thus the nailer will be operated to drive a staple in the bottom of the basket at

the same time that the basket-blanks are being raised to the form and bent around it. 65

Near its upper end the rear wall of the chute is formed with a rearwardly-projecting web or shelf 360, through which extends a short vertical shaft 361, to which is secured above 70 the shelf a wire-feed roller 362, provided with a gear 363, and below the shelf this shaft has secured to it a ratchet-wheel 364. A pressure-roller 365, provided with a gear 366, engaging the gear 363, is journaled on a stud 75 367, carried by a lever 368, pivoted at one end, 370, to the shelf and having its opposite end attached to a spring 372, that causes the roller 365 to be drawn against the roller 362. The ratchet is pushed forward intermittently 80 by a pawl 373, pivoted to a three-armed lever 374, which latter is pivoted to a bracket 375, projecting laterally from the rear wall of the chute. A spring 376 draws the pawl into engagement with the ratchet-wheel, and when 85 the lever 374 is made to actuate the ratchet it does so against the action of the spring 377, that engages the arm 378 of the lever 374 and has one end seated in a triangular bracket 379, projecting from the chute below the shelf 90 360. The outward movement of the lever 374 is limited by an L-shaped stop 380, secured to the bracket 379 and at times engaging the arm 378.

As the chute is moved outward to bring the 95 nailer under the form the outer arm of the lever 374 comes in contact with a pin 381, projecting from the table 6 at the left of the main frame, and as the chute continues in its forward movement the lever 374 is swung, causing the pawl 373 to turn the wire-feeding rolls to feed the wire properly across the channel in front of the staple-forming sleeve and under the anvil before the nailer operates. Enough wire is fed each time that the 100 chute moves forward to make one staple, which is driven in the body-blanks in the manner before described.

I have now described all the mechanism required to make a complete basket; but as the 110 baskets are successively made and deposited in the chute the pile of body-blanks will eventually be exhausted and the chute will be filled with baskets. I have provided the machine with means for feeding new piles of body-blanks to the wells 33 and 34 and for automatically removing the stack of completed baskets from the chute whenever a predetermined number has been made. As before 115 stated, the wells 33, 34 are below the surface of the table 6, and this table is extended to the left, its upper flat horizontal surface being adapted to receive piles of blanks at 383, 384 to the right of the pusher-frame 385 when the latter is at the extremity of its out-stroke, as indicated in Fig. 3. The pusher-frame is shaped, as shown in Fig. 3, in such 120 manner as to hold the blanks at the same an-

gle and in the same relation as they occupy when in the wells 33 34. The pusher is provided with overhanging arms 386, which hold down the piles of body-blanks when they are 5 entering the wells 33 and 34, preventing them from tipping or from falling into the wells until they register therewith and can enter them properly. Upright posts 420 limit the inward movement of the piles of body-blanks 10 and coöperate with the arms 386 to effect the proper disposition of the blanks in the wells.

Most of the parts above described, together with certain other parts connected therewith, are also illustrated in Fig. 73.

15 The pusher-frame has secured to it a downwardly-extending arm 387, that is adapted to move in a slot 388 toward and from the wells. About midway between its upper and lower ends the arm is formed with a long bearing-sleeve 389, sliding on a rod 390, rigidly secured to a bracket 391, projecting downwardly from the shelf 5 of the main frame. The lower end of the arm 387 is rigidly secured to the left-hand end of a horizontal rod 392, 20 reciprocating through bearings in the frame, and to the right-hand end of the rod is adjustably secured a collar 393, to which is jointed one end of a pitman 394, the opposite end of which is jointed to a crank 395 on a 25 horizontal shaft 396, arranged parallel with the drum-shaft and extending from front to rear of the machine. This shaft has a pinion 397 secured to it, which meshes with a pinion 398 of the same diameter on the shaft 48 of the crane-swinging mechanism before referred to. Another pinion 399 is loosely mounted on the shaft 48, and it has a shoe 400 and a hub 401 clutched onto the hub of the pinion 398. The pinion 399 is adapted to gear with 30 a series of teeth 402 on the wheel 14, (see Figs. 49 and 55,) and the shoe 400 is adapted to engage a track 403 on this wheel. During 35 each revolution of the main shaft 11 the pinion 399 is given one revolution by the teeth 402, and the pinion 397 is likewise given one complete revolution; but the shaft 396 is not revolved except at stated intervals, as will be 40 presently explained.

In the machine shown in the drawings the 45 mechanism is so organized that when twenty-five baskets have been constructed and stacked in the chute—*i. e.*, when the main shaft has made twenty-five revolutions—they are expelled from the chute and at the same time 50 two new piles of body-blanks are fed to the wells. The mechanism may of course be organized to perform these operations when any other desired number of baskets have been completed.

55 The body-blanks may of course be fed to the receptacles by hand, and the completed baskets may be merely dropped upon the floor.

On the rear end of the drum-gear shaft 11 is secured a collar 404, which is closed at its 60 rear end, and thus forms a cap that covers the

rear end of the shaft. In this collar is formed a radial slot 405, in which is adjustably arranged a pin 406, to which is pivoted a pawl 407, that engages a ratchet-wheel 408, having twenty-five teeth and mounted to revolve on 70 a stud projecting rearwardly from the frame below the plane of the drum-gears and just over the plane of the shaft 396. On its inner or front face the ratchet-wheel carries a trip-block 410, (see Figs. 2 and 12,) adapted to engage the outer or rear end of a key 411, pivoted in a recess 412 in the rear end of the shaft 396. The block 410 is beveled or inclined, so as to pass over the rear end of the key; but in so doing it presses down the outer end of 80 the key. A collar 413 surrounds the rear end of the shaft 396 and is rigidly secured or bolted to the main frame. It is provided with a narrow recess 414, into which the outer end of the key may be moved by a spring 415. 85 The pinion 397 is formed with a slot 416, into which the flat end of the key is arranged at times to enter, and when the key and pinion are thus engaged the pinion and shaft 396 will revolve together. The organization is such 90 that once in each revolution of the ratchet-wheel the trip-block 410 engages the outer end of the key, unlocks it from the collar, and causes its front end to engage the pinion 397, which then makes a complete revolution and 95 at that time gives a complete revolution to the shaft 396, thus operating the pusher-frame, by means of the connections before described, to feed two piles of body-blanks to the wells 33 34. Since one revolution has been given 100 to the shaft 396, the ratchet is moved forward one tooth and the trip-block is disengaged from the key, which latter is then disengaged from the pinion 397 and engages the collar 413.

The stack of twenty-five baskets is pushed 105 from the chute into an inclined trough 417 by the pusher 418, arranged on the left-hand side of the chute and attached to a horizontal rod 419, that reciprocates from right to left in a bearing 420. The rod is attached to an arm 426, in turn attached to the rod 392, before referred to, which operates the pusher-frame. (See Fig. 73.) It will thus be seen that the baskets are consecutively made and stacked 110 in the chute and that when a predetermined 115 number has been reached (determined by the capacity of the chute and the number of teeth in the ratchet-wheel) the stack is expelled from the chute and delivered to the trough, from which the baskets may be taken either by hand or a suitable automatic conveyer. It will also be observed that when a stack of baskets is 120 delivered from the chute two new piles of body-blanks are supplied to the wells below the pickers.

I have not shown automatic means for supplying new piles of bands. These may be inserted by hand.

The operation of the mechanism has been 125 described in connection with the description 130

of the mechanism itself, but may here be briefly repeated. In the drawings the crane or die-carrier is represented as being over the well 34. When in this position, it has already received one blank and is ready to receive another. The die-carrier next moves with the crossed blanks into position under the form and the band-plungers commence to move bands from the channels toward the form. The chute at the same time starts to move outward to advance the bottom-nailer to a position beneath the form, while the pickers drop onto the piles of body-blanks in the wells. After the bands have been properly placed on the form in the manner illustrated in Fig. 61 the form is given a one-fourth revolution, so as to wrap the bands around it in the manner indicated in Fig. 62, and by this time the chute has moved the bottom-nailer into position under the form and the pickers are rising with body-blanks. Then the crane rises and the body-blanks are bent around the form in the manner illustrated in Fig. 63. At this time the pickers are still rising and the bottom-nailer mechanism operates, after which the form is given a one-half revolution to wrap the bands around the upper edges of the body-blanks in the manner illustrated in Fig. 64. By this time the pickers are raised to their full extent, the chute moves in, withdrawing the bottom-nailer from below the form, and assumes a position directly under the form to receive the completed basket. Immediately after the form has been given the one-half revolution referred to the band-nailers operate to drive staples into the bands and body-blanks, the nailers being given a long stroke, and while the nailers are exerting full pressure on the bands after the driving of the staples the crane lowers. After this is accomplished the form is given a one-fourth revolution, wrapping the ends of the bands completely, as indicated in Fig. 65, and then the nailers operate with a short stroke to drive staples at the ends of the basket. After the bands are thus secured and the crane has been lowered and swung out of the way the form lowers and deposits the completed basket in the chute, immediately rising to its normal position. At this time the band-plungers rise and the die-carrier moves to the well 33, receives a blank therefrom as the crane reverses its movement, and then moves to position over the well 34. When the predetermined number of baskets has been deposited in the chute, the mechanism operates to expel the pile of baskets from the chute and to supply new piles of body-blanks to the wells in the manner before described.

I claim as my invention—

1. In a basket-making machine, the combination with a form, of a crane oscillating in the arc of a circle to bring the blanks to the form, a revolving die carried by the crane,

and means for causing the form to enter the die to bend the blanks.

2. The combination with a form, of a die co-operating therewith, and means for oscillating the die back and forth in the arc of a circle 70 toward and from the form, and for raising and lowering it relatively thereto.

3. The combination with a form, of a crane, means for oscillating it back and forth in the arc of a circle toward and from the form, and 75 for raising and lowering it relatively thereto, and a revolving die carried by the crane.

4. The combination with a form, of a die co-operating therewith, means for automatically supplying the die with body-blanks for the 80 basket, means for oscillating the die back and forth in the arc of a circle toward and from the form, and means for causing the form to enter the die to bend the blanks.

5. The combination with a form, of a die co-operating therewith, means for automatically supplying the die with body-blanks for the basket, means for oscillating the die back and forth in the arc of a circle toward and from the form, and means for raising and lowering 90 the die.

6. The combination with a form, of a die co-operating therewith, a crane on which the die is mounted and on which it is free to revolve, and means for raising and lowering the crane 95 relatively to the form, and for moving it laterally toward and from the vertical plane of the form.

7. The combination with a form, of a die co-operating therewith, a crane supporting the 100 die, a pitman connected with the crane and relatively to which the crane moves vertically, means for actuating the pitman to cause the die to move into and out of position beneath the form, a rotary cam for raising and lowering 105 the crane to cause the die to engage the form, and connections between the cam and crane.

8. The combination with a form, of a die co-operating therewith, a crane on which the die 110 is mounted to rotate, means for automatically placing body-blanks for a basket on the die, a pitman connected with the crane, a cam engaging the crane, a wheel having mutilated gearing and connections between said mutilated gearing and the pitman and cam.

9. The combination with a form of a rotary die having yielding sides.

10. The combination with a form, of a rotary die having hinged sides, and a spring for 120 normally holding the sides at right angles to the axis of the form.

11. The combination with a rotary form of a rotary die, a plate arranged within the die-opening, leaves hinged to the plate and to the 125 die, and a spring for lifting the leaves.

12. The combination with a rotary form, of a rotary die having a movable inner portion and leaves hinged to the die and to the inner portion for the purpose specified.

13. The combination with a rotary form, of a rotary die having hinged leaves and a spring controlling the movement of the leaves.
14. The combination with a form, of a die having yielding side walls, a crane on which the die is mounted to revolve, means for moving the crane toward and from the form, and means for depositing body-blanks for the basket on the die while its walls are extended.
15. The combination with a form, of an oscillating die, means for depositing body-blanks for the basket on the die, and means for moving the die toward the form and for holding it stationary while receiving one of the body-blanks.
16. The combination of a form rotatable about its axis and adapted to reciprocate in line therewith, a chute into which the form descends, a die above the chute movable toward and from the form in line with its axis and also laterally relatively thereto.
17. The combination with blank-bending mechanism, of means for carrying blanks thereto, picker mechanism for depositing blanks on the carrier mechanism, wells or receptacles conforming in shape to the body-blanks of the basket, and placed at an angle with each other, a table and a pusher for moving piles of blanks from the table and depositing them in the wells.
18. The combination with blank-bending mechanism, of means for carrying blanks thereto, picker mechanism for depositing blanks on the carrier mechanism, wells or receptacles conforming in shape to the body-blanks of the basket, and placed at an angle with each other, a table, a pusher having angular walls corresponding with the shape and arrangement of the wells for moving piles of blanks from the table to the wells, and means for operating the pusher.
19. The combination with blank-bending mechanism, of means for carrying blanks thereto, picker mechanism for depositing blanks on the carrier mechanism, wells or receptacles conforming in shape to the body-blanks of the basket, and placed at an angle with each other, a table, a pusher having angular walls corresponding with the shape and arrangement of the wells for moving piles of blanks from the table to the wells, and arms carried by the pusher for holding the piles of blanks in position.
20. The combination with blank-bending mechanism, of means for carrying blanks thereto, mechanism for depositing blanks on the carrier mechanism, a table, wells or receptacles conforming in shape to the body-blanks of the basket, and placed at an angle with each other, and arranged below the level of the table, a pusher for moving piles of blanks from the table into the wells, and means for operating the pusher.
21. The combination with blank-bending mechanism, of means for carrying blanks thereto, means for depositing blanks on the carrier mechanism, a table formed with depressions or wells conforming in shape to the body-blanks of the basket, and placed at an angle with each other, posts attached to the table for guiding the blanks as they are fed to the wells, a pusher for moving piles of blanks from the table into the wells, and means for operating the pusher.
22. The combination with blank-bending mechanism, of means for carrying blanks thereto, picker mechanism for depositing blanks on the blank-carrying mechanism, a table, a pusher for moving piles of blanks from the table into position below the picker mechanism, and mechanism for automatically actuating the pusher after a predetermined number of baskets have been constructed and the supply of blanks has been diminished.
23. The combination with basket-forming mechanism, of a chute which receives the completed baskets, and means for automatically discharging the stack of baskets from the chute when a predetermined number has been made.
24. The combination with basket-forming mechanism, of a chute which receives the completed baskets, a pusher for discharging the baskets from the chute, and means for automatically actuating the pusher after a predetermined number of baskets has been made.
25. The combination with basket-forming mechanism, of a chute for receiving the completed baskets, a pusher for discharging the baskets from the chute, a rotary shaft, connections between the shaft and the pusher, a pinion mounted on said shaft, a key for operatively connecting the pinion with the shaft, and means for automatically actuating said key to lock the pinion to the shaft and to unlock it therefrom.
26. The combination with basket-forming mechanism, of a chute for receiving the completed baskets, a pusher for discharging the baskets from the chute, a rotary shaft, connections between said shaft and the pusher, a pinion mounted on said shaft, a key for operatively connecting the pinion with the shaft, a wheel actuated from the main shaft of the machine and rotating continuously, and a device carried by said wheel for at stated periods actuating the key to connect said before-mentioned pinion with the shaft on which it is mounted.
27. The combination with basket-forming mechanism, of blank lifting and depositing mechanism, a pusher for feeding piles of blanks into position below the blank-lifting mechanism, a chute for receiving the completed baskets, a pusher for discharging the completed baskets from the chute, and mechanism for automatically and simultaneously actuating the blank-pushers and basket-pushers after a predetermined number of baskets have been made.

28. The combination with a form, of a basket-receiving chute having open sides, hooks pivoted to the upper ends of the chute on one side, and a hook pivotally connected with the 5 rear wall of the chute and having a laterally-projecting arm extending toward the front wall of the chute.

29. The combination with the blank-carrying die, of means for raising a blank from its 10 receptacle, comprising a picker-head having a concaved lower surface communicating with the outside, for the purpose specified.

30. The combination of a picker-head, means 15 for moving it toward and from a pile of blanks, needles carried by the picker-head, and means for moving them diagonally relatively to the line of movement of the picker-head.

31. The combination of a picker-head, a picker-bar connected therewith and movable 20 relatively thereto to a limited extent, needles carried by the picker-head and means for moving the needles diagonally relatively to the line of movement of the picker-bar.

32. The combination of a picker-head having a blank-flattening face, means for moving the picker-head, needles carried by the picker-head, a means for moving the needles diagonally relatively to the line of movement of the picker-head to cause them to project below 25 the blank-flattening face thereof into a blank.

33. The combination of a picker-head, means for moving it, needles on opposite sides of the picker-head and means for moving the needles 30 toward each other diagonally with reference to the line of movement of the picker-head.

34. The combination of a picker-bar, a picker-head carried thereby and movable to a limited extent thereon, needle-carriers mounted 35 in the picker-head and adapted when depressed to register with the lower surface of the picker-head, diagonally-arranged needles on the carriers and means for operating the needle-carriers.

35. The combination of the picker-bar, the picker-head carried thereby and movable thereon, means for causing a friction to be exerted between the bar and the head, needle-carriers supported by the picker-head, and devices for actuating the needle-carriers as the head moves relatively to the bar.

36. The combination of the picker-bar, the picker-head carried thereby and movable thereon, levers carried by the picker-head, diagonally-operating needles carried by the levers, and devices for actuating the levers while the head is moving relatively to the bar.

37. A blank separating and lifting mechanism, comprising means for pressing and flattening the blanks, means for driving needles diagonally into a blank, mechanism for raising the needles, and means for withdrawing the needles from the blank after it has been raised.

38. In a basket-making machine, the combi-

nation with a form, of a hook for engaging the end of a band, a rod moving in the form and gripping the band in the hook, and means for actuating the grip-rod.

39. In a basket-making machine, the combination with a form of two hooks for engaging the ends of two bands, grip-rods sliding in the form and adapted to engage the ends of the bands in the hooks, and means for simultaneously operating the grip-rods.

40. The combination with a form, of hooks for engaging the bands carried by the form, grip-rods co-operating with the hooks, levers to which the grip-rods are connected, a stationary cam, and a device carried by the levers and engaging the cam whereby the grip-rods are periodically actuated.

41. The combination with a form, of hooks carried thereby to receive the ends of the bands, grip-rods carried by the form and adapted to engage the bands in the hooks, channels above the form into which the ends of the bands are fed, means for delivering the bands to these channels, oscillating pushers for forcing the bands from the channels into engagement with the hooks, and means for actuating said pushers.

42. The combination with a form, its shaft, band-feeding shafts parallel therewith, a cross-head adapted to slide vertically on the form-shaft, oscillating band-plungers thereon, and means for raising and lowering said cross-head.

43. The combination with the form and its vertical shaft, of a cross-head adapted to move vertically on said shaft, oscillating band-plungers pivotally connected with the cross-head, mutilated gearing connected with the cross-head for raising and lowering it at intervals, vertically-moving friction-plates and connections between the band-plungers and the friction-plates, for the purpose specified.

44. In a basket-making machine the combination with a form, of a hook for engaging the end of a band, a gripping device moving in the form and gripping the band in the hook, and means for actuating the gripping device.

45. The combination of an oblong form revoluble about its own axis, of a band-holder movable positively and independently of the form during each quarter-turn thereof about its axis, and which holds the band close to the side of the form.

46. The combination with a revolving oblong form, of a band-holder movable independently of the form about the axis thereof to hold the band close to the side of the form as the latter revolves.

47. The combination with a revolving oblong form, of band-holders movable independently of the form about its axis and which hold the bands close to the form as the latter revolves.

48. The combination with a revolving form having band-hooks at two diagonally opposite

corners, of band-holders which receive the bands at the diagonally opposite corners of the form not having hooks, and which are moved toward the ends of the form provided with hooks as the form revolves.

49. The combination with a revolving oblong form, of band-holders and means for moving them alternately in opposite directions to move the bands toward and from the axis of the form, and thus hold them close to the sides of the form.

50. The combination with the form and its rotating shaft, of band-holders that swing back and forth around the axis of the shaft, and means for actuating said band-holders from the form-shaft.

51. The combination of the revolving oblong form and its shaft, of a gear on the shaft, a pinion driven by said gear, band-holders and operative connections between the band-holders and the pinion for moving the holders to cause their outer ends to hold the bands close to the sides of the form.

52. In a basket-making machine, the combination with an oblong form about which the parts of the basket are assembled, and nailing mechanism provided with devices for giving it both a long and a short stroke, for the purpose specified.

53. The combination with an oblong form of the staple forming and driving mechanism, and operating mechanism for giving the staple-driving mechanism successive alternate long and short strokes.

54. The combination with an oblong form about which the parts of a basket are assembled, of nailing mechanism and means for operating it to give to the staple formers and drivers alternately a long and a short stroke.

55. The combination with an oblong form about which the parts of a basket are assembled, of nailing mechanism, means for operating the nailing mechanism to give to it a long stroke when a side of the form is presented to the nailing mechanism, and to give to the latter a short stroke when the end of the form is presented.

56. The combination of an oblong form, means for giving to it partial revolutions successively, with intermediate pauses, and nailing mechanism having successive long and short strokes, for the purpose specified.

57. The combination of an oblong form, the band-nailing mechanism, a crank-pin, connections between said crank-pin and the band-nailing mechanism, means for rotating said crank-pin, and devices for shifting the position of said crank-pin radially with reference to the axis about which it rotates.

58. The combination of an oblong form, band-nailing mechanism, a crank-pin connected therewith, a crank in which the crank-pin is radially adjustable, mutilated gearing for operating said crank, an eccentric-strap to which the crank-pin is connected, an eccen-

tric within the eccentric-strap, and mutilated gearing for rotating the eccentric.

59. The combination with a rotating oblong form about which the parts of a basket are assembled, of nailing mechanism coöperating with the form and having a differential movement, substantially as described.

60. The combination with a rotary form, having band-hooks on diagonally opposite corners, of four vertically-reciprocating band-plungers, and hooks for supporting the bands and giving tension thereto, substantially as described.

61. The combination of a reciprocating and revoluble form, of a chute for receiving baskets from the form, means for reciprocating the form into and out of the chute, nailing mechanism supported by and traveling with the chute, and adapted to nail the body-blanks of a basket together, and means for reciprocating the chute back and forth under the form to alternately bring the upper opening of the chute and the nailing mechanism into line with the form.

62. The combination with a form about which the basket is constructed, of a chute, the gear and crank mechanism for moving it beneath the form, bottom-nailing mechanism carried by the chute, and mutilated gearing for operating the bottom-nailing mechanism periodically.

63. The combination of a revoluble form, a die-plate coöperating therewith, and having hinged side walls and a central opening, a revoluble carrier for the die, and bottom-nailing mechanism operating through said die.

64. In a basket-making machine, the combination of a series of mutilated gear-wheels, an oblong form, a die coöperating therewith, band-feeding devices, band-nailers, and connections between said mutilated gear, the form, the die, the band-feeding and band-nailing mechanisms, whereby the form is rotated and reciprocated, the die is raised and lowered, and also moved laterally, the band-feeding mechanism is actuated to feed bands to the form, and alternate long and short strokes are given to the nailing mechanism.

65. In a basket-making machine, the combination of an oblong form, means for feeding two bands to opposite ends thereof, means for attaching the bands to the form, means for then giving to the form one-fourth of a revolution, means for bending body-blanks about the form, means for then giving a one-half revolution to the form, means for then nailing the bands to the body-blanks, means for giving a further one-fourth revolution to the form, and means for then again nailing the bands to the body-blanks.

66. In a basket-making machine, the combination of an oblong form, means for attaching the ends of bands to opposite ends of the form, means for then giving a one-fourth revolution to the form to wrap the bands around it, means

for then bending body-blanks around the form, and for attaching the body-blanks together at the bottom of the form, means for then giving to the form a one-half revolution to wrap the bands around the body-blanks, means for then nailing the bands, means for giving an additional one-fourth revolution to the form, and means for further nailing the bands.

67. The combination in a basket-forming mechanism, in which the band is carried from the inside to the outside of the basket sides, of means for positioning two or more bands at different points peripherally of the basket being

formed and carrying them around the basket so that all the basket sides will be connected by the bands both inside and outside without necessarily carrying a band completely around the periphery both inside and outside the basket. 15

In testimony whereof I have hereunto subscribed by name.

EMMET HORTON.
